The ornamental design for an electric vehicle charging station, as shown and described.

DESCRIPTION

FIG. 1 is a left side elevational view of an electric vehicle charging station showing our new design;

FIG. 2 is a rear elevational view thereof;

FIG. 3 is a right side elevational view thereof;

FIG. 4 is a top plan view thereof;

FIG. 5 is a front elevational view;

FIG. 6 is a rear perspective view thereof; as seen from the left side thereof; and,

FIG. 7 is a front perspective view thereof, as seen from the right side thereof.

The broken lines shown in FIGS. 1-3 and 6-7 provide boundaries for grayed out regions which define subject matter that forms no part of the claimed design.
